 tion

Application March 20, 1931, Serial No. 524,116
 Renewed May 14, 1937

43 Claims. (Cl. 197—16)

This invention relates to writing machines or typewriters of the character having changeable type which are supported or borne by a shuttle, the invention having for its primary object to provide an improved combination of mechanisms in the machine for carrying out the writing operation.

Heretofore two kinds of typewriting machines have been provided each having its own advantages as well as its limitations. For example, one type of machine has type bars, operable by key levers, to print against a work sheet on the platen. This type of machine possesses the desirable feature of permitting the work sheet to be introduced for printing without rolling up said work sheet. It further possesses the highly desirable feature of a four bank key board. It also has the limitation of a single set of types.

The other type of machine has a type shuttle which may be in the form of a wheel or segment, with types thereon with which a hammer engages to perform the printing on an interposed work sheet. This type of machine possesses the desirable feature of interchangeability, the type shuttle being replaceably mounted in the machine, but it also possesses the feature, which is sometimes objectionable, of rolling up the work sheet for insertion into a basket from which it is fed to the printing point. This type of machine has also been limited to a three bank key board.

An object of the present invention is to provide a machine which possesses all of the advantages of both types of machines, in other words, a machine having a four bank key board, changeable type sets, and the feature of accommodating the work sheet without rolling it up; the machine being simple in construction so that it may be manufactured to sell at a price which compares favorably with the other commercial typewriting machines on the market.

Another object of the invention is to provide a writing machine with an improved operating shuttle.

Another object of the invention is in providing the operating shuttle with improved means for demountably securing a type bar holder thereto.

Another object of the invention is to provide a machine which will give a greater latitude of changeability of types than has been possible heretofore. To this end the replaceable type bar carrier is constructed in a manner such that each type bar thereon may be replaced by one having a different character consistent with a certain class of work or job to be typed on the machine.

55 This feature of differently arranging the types

on a demountable type carrier is extremely economical over constructions formerly used in which the types have been formed directly thereon, and where, in order to meet the type arrangement required by a customer, it has been necessary to make up a complete shuttle in accordance with each variation of the arrangement of types. This has necessitated the expensive operation of making a new die by which the type shuttle is subsequently moulded. With the structure of the present invention it is merely necessary, when a special arrangement of types is required, to take a standard type carrier out of stock at the factory and change the type bars therein to suit the requirement of the customer. This change may also be made by a repair man in the field if a change of type character is required after the type carrier has been in use for some time.

A further object of the invention is to provide the type bar holder with improved means for supporting, guiding and restoring the type bars thereon.

Still another object of the invention is to provide an improved combination of means between a key lever and the shuttle for locating the various type bars at the hammer which hammer is in alignment with the printing point.

A still further object of the invention is to provide a power mechanism such as a continually running motor for operating the type carrying shuttle to a selected typing position and another power mechanism such as a solenoid which is operated, after the shuttle has been moved to the selected position, to actuate the hammer to strike the selected type bar of the shuttle.

Another object of the invention is to provide novel means operable by the key levers to effect a connection of the type carrying shuttle with the motor so as to drive the shuttle to its selected position by the motor.

40 Another object of the invention is to provide a writing machine with an improved combination of a plurality of type disposed forwardly of the platen roller and a striking hammer cooperable with the type disposed in front thereof.

Still another object of the invention is to provide means operable by the key levers to select a position at which the type carrying shuttle will be stopped, and means including a device simultaneously operable therewith to cause the motor to actuate the device to operate the shuttle to the selected position whereby the particular type of the shuttle corresponding to the operated key lever will be positioned in alignment with the hammer, the operation of which hammer is effect- 55

ed when the motor driven device has reached the end of its travel.

A still further object of the invention is to provide the shuttle with improved locking means to prevent rebound of the shuttle when it strikes the stop pin and for holding the shuttle in its set position during striking operation of the hammer on the positioned type, said locking means being effective in either direction in which the shuttle 10 may be moved from its home position.

Other and further objects will appear in the specification and be specifically pointed out in the appended claims, reference being had to the accompanying drawings, exemplifying the invention, and in which:—

Figure 1 is a vertical longitudinal section taken through this improved writing machine on a fragmentary staggered line.

Figure 2 is a vertical transverse section taken 20 approximately on the line II—II of Fig. 1.

Figure 3 is a fragmentary vertical longitudinal section taken approximately on the line III—III of Fig. 2.

Figure 4 is a fragmentary vertical section taken 25 approximately on the line IV—IV of Fig. 6.

Figure 5 is an enlarged fragmentary vertical section taken through the type holder approximately on the line V—V of Fig. 2.

Figure 6 is a rear view of the writing machine. 30

Figure 7 is a fragmentary plan view of Fig. 6. Referring by numerals to the accompanying drawings 1 designates the writing machine frame having the usual sidewalls 2 and rear end member or wall 3 joining the walls 2 and longitudinally disposed within the frame 1 are the key levers 4 each having a denoting key 5, said key levers near their rear ends being swingably mounted on the transverse shaft 6 which is supported in opposite sidewalls 2.

40 Some of the key levers are provided each with an upwardly extending cam lug 7, the lugs 7 being in approximate transverse alignment and disposed adjacent said lugs and extending transversely across the frame 1 is a fixed or rigidly held vertically disposed supporting bracket or plate 8 suitably supported on the machine frame 1. Said plate supports a series of horizontally disposed stop pins 9 which are located in respective openings 10 formed in said plate, each stop pin 50 having a head 11 and a spring 12 interposed between each head and the back of the plate 8.

The key levers 4 are divided into groups A and B, the group A being disposed in approximately one-half of the frame 1, or in other words to 55 the right of the middle of the machine (Fig. 2) and the group B being disposed in the approximate other half of the frame, to the left of the middle of the machine, the key levers of said groups A and B having cooperation with frames or levers C and D respectively which are located 60 at the rear of the machine frame 1 and are hereinafter described.

The pin openings 10 of the plate 8 are disposed 65 intermediately of the width of the plate 8, said openings and the stop pins 9 carried thereby having relation with the intermediately located key levers of the groups A and B. The plate 8 is further provided with openings 13 at each side of the openings 10, each of said openings having 70 therein a stop pin 14 of respective intermediate or auxiliary levers 15 pivoted at 16 on the rear side of the plate 8, each lever 15 being operable by a cam lug 17 of the outer disposed key levers of the groups A and B as shown in Figs. 2 and 3.

75 From an inspection of Fig. 2 which clearly

shows the location of the intermediately disposed openings 10 in the plate 8 for the support of stop pins or selecting devices 9 and the outer disposed openings 13 for the stop pins or selecting devices 14, it will be understood a stop pin corresponding to each key lever 4 is provided. It is also to be noted that the manner of operating the inner disposed stop pins 9 is different than the manner in which the stop pins 14 are operated. In this connection when one of the inner key levers 4 is depressed, the cam face 18 acts against the head 11 of a respective pin 9 to move the forward end of the pin outwardly on the plate 8. When one of the outer key levers 4 having the cam lug 17 is depressed, the cam face 19 thereof will force 11 the lower end of the lever 15 rearwardly and thus move the pin 14, at the upper end of said lever, forwardly, said pin being supported on the plate 8.

Extending forwardly from the bracket or plate 8 is a rigidly held horizontal pin 20 for the support 24 of a ball bearing race 21 and mounted on said ball bearing race is an oscillatory shuttle 22. Secured to said shuttle on the rear side thereof, and located between said shuttle and the plate 8, is a pinion 23, said pinion being disposed concentric 25 to the pin 20. Horizontally disposed above the pinion 23 and supported on guides 24 which are struck from the plate 8 is a rack 25 having the teeth 26 in mesh with the teeth of the pinion 23, said rack at one end being provided with a pin 27 30 connected to suitable operating mechanism hereinafter described.

The shuttle 22 is provided with a vertically disposed arm 28 and a pair of horizontally disposed arms 29, each arm supporting a threaded stud 30 35 on its outer end and mounted on each stud is a thumb nut 31, the studs and thumb nuts being for demountably securing a type bar holder 32 to the shuttle or bracket 22.

The type bar holder 32 is in the form of a segment and when mounted on the shuttle 22 is concentric therewith, said shuttle having bifurcated ears 33 for engagement on respective studs 30. The type bar holder 32 is provided with a series of equally spaced radially disposed slots or grooves 40 34, the number of grooves corresponding to the number of key levers 4 of a four bank key board machine there being forty-two key levers shown (Fig. 2). There is also a total of forty-two stop pins 9 and 14 in the writing machine, each groove 50 34 being for the reception of a type bar 35 each of which is guided in a respective groove to swing about the pivot wire 36. The type bars are all straight and extend radially outwardly from the convexed surface of the holder 32, each type bar 55 being guided almost throughout its entire length in the slot to insure accurate printing, only that portion projecting which supports the type block 38.

From the foregoing it will be understood that 60 the type bar holder 32 with its set of type bars thereon may readily be detached, from the shuttle or bracket 22, and another one having a different style of types thereon may readily be substituted therefor. It should also be understood 65 that any one of the type bars of the set may be substituted, at the factory or by a field man, by another one bearing a different character, by first bending the pivot wire 32 at either end back to the 70 curvature of the major portion of the wire, and then sliding the wire around until the end passes the type bar which is to be substituted by another one. Subsequently the wire may be pushed back to re-assemble all of the type bars which have 75

been temporarily removed during the substitution of one or more.

The type block 38 of each type bar may be made of type-metal or any other desirable material and each is mounted on the outer end 31 of each type bar. On each type block the types may be disposed one above the other as shown in Figs. 1 and 5. Drilled in each groove 34 of the type holder near the outer end of each groove is a spring pocket 39 for the reception of a spring 40, each of said springs normally holding its associated type bar 35 in its normal or retracted position, the heel portion 41 of each type bar abutting with the bottom portion 42 of respective grooves for limiting the return movement of each type bar.

The levers C and D heretofore mentioned are swingingly mounted on a horizontally and transversely disposed shaft 43, said shaft being supported in end bearings 44 which are in the form of lugs extending from the rear member 3 of the machine frame and the intermediate bearing 45 which is extended from the vertical post 46 of the rear member 3, each of said levers C and D comprising a pair of vertically disposed arms 47 which are joined at their upper ends by a horizontal transversely extending portion 48, said portions 48 paralleling the shaft 43. Each of the portions 48 of respective levers C and D is provided with a dove-tailed groove or guide way 49 and slideable, laterally of the machine, in each guide way is a shoe 50.

Disposed adjacent the rear of the writing machine and near the upper portion thereof is a horizontal transversely extending bar or actuating element 51, said bar intermediate of its ends being slidably mounted in a bearing 52 fixed on the machine frame. Mounted on said bar at each side of said bearing is one of two equalizing springs 53 and slidably engaging said bar at the outer end of each spring 53 is a pawl 54. Mounted on said bar and at the opposite side of each pawl is an equalizing spring 55 which is located between the pawl 54 and a collar 56 fixed on said bar.

One end of the bar 51 is bifurcated as designated at 57 and secured to said bar in said bifurcation by a pin 58 is one end of a lever 59, the end of the lever through which the pin 58 passes having an elongated opening 60. The lever 59 is pivoted on the frame 1 of the writing machine by the screw 61, the opposite or forward end of said lever being pivotally connected to the pin 21 borne by the rack 25 which is in mesh with the pinion 23 of the shuttle 22.

Secured to the vertical post 46 of the rear member 3 of the frame 1 is a bracket 62 to support an electric motor 63 which constitutes a driving means for the shuttle. Extending equal distances from each end of the motor is a motor shaft or rotating device 64, one end of the motor shaft having a left hand threaded length or screw 65 whereas the other end of the motor shaft is provided with a right hand threaded length or screw 66.

Each shoe 50 on its inner end is provided with an upwardly extending ear 67, each being secured to a respective pawl 54 by rivets 68. The outer end of each shoe is provided with a vertically extending ear 69 and secured to each ear 69 and suitably insulated therefrom is a contacting plate 70 which is in transverse and horizontal alignment with a pair of electrical contact pins 71, each pair of contact pins 71 being supported by a lug

72, of insulating material, and secured to the rear member 3 of the frame 1.

The end of each pawl 54 which engages the bar 51 is provided with an elongated slot 73 so that the pawl may be moved transversely of said bar and the opposite end of each of said pawls has a thread-engaging tooth as designated at 74, the teeth 74 to engage the screws on the motor shaft 54. On the lower edge of each lug 75, each lug being cooperable with a respective guide strip 76, each of which is secured to the rear member 3 of the frame 1 beneath each pawl.

Each of the levers C and D at its lower end is provided with a horizontally disposed universal 15 bar or treadle 77, the treadle 77 of the lever C overlying the rear ends of the group A of key levers 4 and the universal bar or treadle 77 of the lever D overlying the rear ends of the key levers 4 of the B group on the other side of the 20 writing machine.

To cause the type bar 35 to print there is provided a hammer 78 which is located in alignment with the printing point and which is formed on the upper end of a vertically disposed lever 79 25 which is located in front of the type carrying shuttle 22, said lever at its lower end being pivotally connected at 80 to the plunger armature 81 of a solenoid having a coil 82 which is horizontally supported in the machine above the key 30 levers 4 and in the approximate longitudinal center of the machine. The lever or printing element 79 is pivoted intermediate its ends at 83 to a stationary supporting bracket 84.

The openings 10 and 13 of respective stop pins 35 9 and 14 are arranged in a curve concentric with the supporting pin 20 or axis of the shuttle 22 so that the pins 10 and 14 are all within range of the stopping projection 85 formed on the end of the depending arm 86 of the shuttle 22. Carried by said arm 86 is a slideable latch or anti-rebound device 87 having a beveled catching portion 88 disposed on one side of the projection 85 and a beveled catching portion 89 disposed on the other side of said projection 85, said catching 45 portions 88 and 89 and the projection 85 being adapted to snap over the active stop pin 9 or 14 and forming retaining notches 90 and 91 on respective sides of the projection 85. It will be understood that the latch through the medium of 50 the portions 88 and 89 prevents rebound of the shuttle stop 85 from the active pin to thus prevent printing out of alignment with the printing point.

The conductor wires 92 and 93 of the contact 55 pins 71, Fig. 6, on each side of the machine are in an electrical circuit (not shown) with the solenoid coil 82.

As shown in Fig. 2, certain of the type bars 35 are lacking in the gaps E indicated on the type 60 holder 32. This is for the purpose of more clearly showing the type bar grooves 34 and the spring pockets 39. In a complete machine however, the type holder 32 is provided with a complete set of 65 type bars.

In this improved writing machine, each key lever is associated with a specific type bar of the set of type bars carried by the type holder 32, and upon the depression of a particular key lever, the mechanism of the machine will be caused to 70 be operated so that the corresponding type bar on the type holder 32, will be moved to the vertical center as indicated by the dotted line F, in striking alignment with the hammer 38 for printing a 75 character from the particular or selected type.

The operation is as follows:—

The motor is put into operation by a switch, not shown, to continually revolve the shaft 64 thereof. When a denoting key 5 is depressed, 5 the key lever 4 thereof at its forward end is moved downward and by reason of said lever being swingably mounted on the shaft 6, the rear end 94 thereof will be swung upwardly thereby elevating the universal bar or treadle 77 and caus-

10 ing the frame or lever C to swing rearward on the shaft 43. This rearward movement of the lever C will carry the shoe 50 thereof rearward and as the pawl 54 is fixed to the ear 67 of said shoe by the rivets 68, the teeth 74 of said pawl will be 15 brought into engagement with the left hand thread 65 of the motor shaft 64, the elongated slot 73 of said pawl permitting the pawl to be moved transversely of the shaft 51 to connect the pawl with the motor shaft.

20 The lateral movement given to the pawl 54 will cause the depending lug 75 thereof to engage and be held on the outside of the guide strip 76 on the lever group A side of the machine (see Fig. 4), and as the motor shaft 64 is revolving, 25 the teeth 74 of the pawl 54 will be acted on by the left hand threaded length 65 and the pawl 54 will be moved leftwardly in Figs. 6 and 7, the guide strip 76 holding the pawl in engaged position with the threaded portion or screw 65 30 while it is moving along said screw. The outward travel of the pawl 54 will compress the spring 55 on the bar 51 sufficiently to act upon the associated collar 56 so that the bar 51 is moved in the same direction thereby swinging the lever 59 on its pivot screw 61, the forward end of said lever 59 which is engaged at 27 to the rack 25 causing said rack to be moved in the direction of the arrow 95 shown in Fig. 2 or in other words, leftwardly of the machine.

40 In addition to the downward depression of the key lever 4 actuating the lever C, simultaneously therewith the cam face 18 of the leg 7 of said lever will engage the head 11 of the associated pin 9 to actuate the latter to project its forward end into the path of the projection 85 of the arm 86 of the shuttle 22, the operated pin 9 determining the position at which the shuttle 22 will be stopped when the shuttle is actuated by lever 59 through the medium of the rack 25 and pinion 23.

50 When the shuttle arm 86 reaches the actuated pin 9 or 14 the catching portion 88 of the latch 87 snaps over the selected stop pin and while the pin 9 engages the stopping projection 91 of the shuttle, the latch is drawn into locking position by the spring 96 of said latch and the pin 9 will be engaged in the notch 90 between the catching portion 88 and the projection 85, the catching portion 88 thereby holding the shuttle 60 against return movement.

As the shoe 50 reaches the end of its travel by reason of the pawl 54 engaging the left hand thread 65, the plate 70 of said shoe will engage the related contact pins 71 thereby closing the 65 electrical circuit of the solenoid 82 by which the armature 81 will be drawn inwardly of the solenoid coil thereby causing the hammer 78 of the lever 79 to strike the type bar 35 which has been moved into alignment therewith and which type bar corresponds to the particular key lever 4 operated.

70 During the striking operation of the hammer 78 on the position type bar 35, the desired character 38 will print on the work sheet on the platen 75 of the carriage 98 which is disposed rearward-

ly of the type carrier 22. As each type bar will carry a pair of type characters one above the other, the upper character will be used for printing by shifting the platen into printing position with the upper character in the usual manner.

75 After printing, the key lever is returned to its normal position by a spring element or the like (not shown) and the stop pin 9 will be returned by the spring 12 thus releasing the shuttle for return movement.

The pawl 54 after completing its travel by means of the left hand thread 65 will be permitted to be released by the lug 75 thereof riding off the guide strip 76 and the spring 99 of the lever C will return said lever to its neutral 15 position as shown in Fig. 1. Upon the release of the pawl 54, the spring 55 which was compressed by the pawl to effect the longitudinal movement of the bar 51 for actuating the lever 59, will be released so that it can expand to an 20 equalizing position with the other springs 53 and 55 on said bar 51, and thus return the pawl 54 into its neutral position. As the bar 51 was moved by the pawl 54 relatively to the immediately disposed bearing 52, the other pawl 54 25 (at the right in Figs. 6 and 7) was also caused to travel on the bar 51 by its associated spring 55, located between said pawl and the collar 56 secured to the shaft 51 although said pawl 54 which is associated with the other half B of the 30 key levers was not brought into engagement with the right hand threaded portion 66, the travelling movement therefore given to the latter pawl 54 being an idle movement caused by the spring 55, said pawl being returned to normal axially 35 of the shaft 51 by the spring 53.

As the bar 51 is moved to its normal or central position, the lever 59 which is secured to one end of said bar by the screw 61 will also return the shuttle 22 to its normal position through the 40 rack 25 and pinion 23.

Obviously, the release of the pawl 54 from engagement with the left hand thread 65 of the motor shaft 64 will cause the electrical circuit in which the solenoid 82 and pins 71 are located 45 to be broken by reason of the plate 70 of the shoe 50 being withdrawn from contact with the pins 71. Upon the breaking or opening of the electrical circuit, the striking hammer 78 of the solenoid 82 is swung to its normal position by 50 means of a spring 82a.

When a key lever 4 of group B is depressed at its denoting end, the universal bar or treadle 77 of frame or lever D will be elevated by the rear end 94 of the depressed key lever thereby causing the lever D to swing rearward on the shaft 43 and carry the pawl 54, supported on the lever D, into engagement with the right hand thread 66 of the continually revolving motor shaft 64.

The engagement of the toothed end of the pawl 60 54 with the revolving right hand thread 66 will cause the pawl to be moved outwardly along the shaft 64 thereby compressing its related spring 55 on the bar 51 sufficiently to act upon the adjacent collar 56, the action of the pawl against the 65 spring 55 and collar 56 causing the bar 51 to be moved in the same direction but in an opposite direction to which it is moved when a key lever 4 of the A group is depressed and consequently the rack 25 in mesh with the gear 23 will swing the 70 shuttle 22 in an opposite direction or counter-clockwise in Fig. 2.

It is to be noted that the key levers 4, of both the A and B groups, which are located near the middle of the machine, are provided with the cam 75

lugs 7 and act directly on the pins 9 whereas the outer disposed key levers 4 are provided with the lugs 17 which act on stop pins 14 through the medium of intermediate levers 15. This arrangement of intermediate levers 15 is provided for the reason that the stop pins 14 on each side of the supporting plate 8 are disposed in an arc struck from a center coinciding with the axis of the pin 20 about which the shuttle 22 oscillates, said arc 10 extending upwardly and outwardly. Some form of connection is therefore required, such as the levers 15, between the cam lugs 17 of the outer key levers and the pins 14, each stop pin 14 having a spring 14a mounted thereover for keeping the 15 lower end of its associated lever 15 against its cam face 19 of the lug 17.

When one of the outer disposed key levers 4 having a lug 17 is operated, the associated lever C or D is tilted rearwardly for connecting the 20 associated pawl 54 with the respective threaded part of the motor shaft 64 to effect the actuation of the bar 51, lever 52 and rack 25 to actuate the type carrying shuttle 22 by the pinion 23 engaged by the rack. Simultaneously therewith the lug 25 17 will force the lower end of the lever 15 rearwardly to move the associated pin 14 forwardly to project its end into the path of the projection 35 of the shuttle 22 for setting the selected type bar 35 in alignment with the hammer 78 for 30 actuation, to print against the platen, by said hammer. Upon the release of the operated key lever 4, all of the actuated parts will be returned to their normal positions, said key lever permitting the return of the operated frame C or D 35 to effect the release of the pawl 54 from its associated threaded part of the motor shaft 64, whereupon the springs 53 and 55 will return the bar 51, lever 59 and shuttle 22, the stop pin 14 of lever 15 being forced from the path of travel of 40 the projection 35 of the shuttle 22 by the spring 14a when the key lever 4 is released. As the bar 51 moves back to normal from either side of its machine the active switch plate 70 leaves the contact pins 71 to open the circuit in which the coil 82 of the solenoid is connected thus deenergizing the solenoid and permitting the return of 45 the hammer 78.

It will be understood that the type bar shuttle 22 moves through different angular distances depending on the selected type bar, the extent of movement depending on the active stop pin corresponding to the selected type bar and the associated key lever. Further that the active connecting pawl 54 moves always the same distance laterally of the machine irrespective of the extent of angular movement of the shuttle. Consequently the element 55 which transmits movement of the pawl 54 to rod or bar 51 is resilient or in the form of a spring to compensate for such variable movements of the shuttle. In other words, when one of the inner type bars is selected the shuttle 22 is arrested early before the pawl has moved the full length of the screw on the motor shaft 64. Under these conditions the pawl 60 continues to move laterally and further compresses the spring 51 until the outer end of the screw is reached by said pawl. Thus each spring 65 55 serves as a compensation device by which the shuttle is moved a variable distance by the pawl 55 having a movement the extent of which is always constant.

It will further be understood that when the rod or actuator 51 is being moved leftwardly in Fig. 7 by the pawl 54 at the left through the medium 75 of the associated spring 55, that the springs 53

and 55 at the right in Fig. 7 are being compressed because they are located between the fixed support 52 and the collar 56 fixed on the rod 51, and that when the rod is moved rightwardly that the springs 53 and 55 at the left in Fig. 7 are compressed. Thus it follows that upon the release of the shuttle from its active position the compressed springs 53 and 55 serve to return it to normal through the rod 51 and the connected parts including the lever 59, rack 25 and pinion 23, the 10 force of the two sets of springs, one set at each side of the fixed support 52, balancing each other to hold the shuttle in a central or normal position. It will also be understood that while one of the springs 55 functions to drive the actuator 15 bar 51 the other spring 55 acts as a return spring for said bar assisted by the associated spring 53. A further purpose of each spring 53 is to assist in holding the associated pawl 54 in its proper position lengthwise of the bar 51, the force of the 20 spring 53 balancing that of the spring 55 when the pawl 54 is in its normal position at the inner end of the screw or worm on the motor shaft and at the inner end of the locking plate 54.

The type bar holder 32 is demountably secured 25 to the shuttle 22 and in the use of a writing machine of this improved character, several type holders 32 are provided, each bearing a different style of characters, and in the event the operator has occasion to change the writing of the machine 30 to a different style of type, the holder 32 can be readily removed by loosening the thumb nuts 31 to remount a holder having the desired style of type. It will be understood that the studs serve 35 not only to enable the detachability of the type bar holder but they also serve to accurately locate said holder on the shuttle with respect to the printing point and with respect to the hammer 78.

Obviously constructional modifications of the 40 device are possible without departing from the spirit of the present invention and therefore it is to be understood that it is not necessary to limit the invention by the terms used in the foregoing 45 description, excepting such as the state of the art may require.

The unique disposition of the type carrier 22 in the writing machine and the vertical transverse swinging thereof, permits its location between the striking hammer 78 and the platen roller 97 so that the type bars 35 of the type carrier 22 can be desirably actuated to print on the record sheet of the platen roll 97.

What I claim is:—

1. In a typewriting machine, the combination 55 of a platen, a type bar unit located at the front of said platen, a type bar actuator in front of said platen, said unit including a body having a thin web, a thick flange on the outer edge of said web, said flange having radial slots therein, 60 a pivot wire in said flange, and type bars supported on said pivot wire, one of said type bars located in each slot, the type bars extending outwardly from said body, selecting means for locating any one of the type bars between the actuator and the platen, and means to operate the actuator.

2. In a typewriting machine including a platen, and an actuator, of a type bar unit having type bars which may be operated by said actuator one 70 at a time to print against the platen, means whereby the type bars may be moved selectively into cooperative relation with said actuator, a bracket, and means for demountably attaching the type bar unit to said bracket to facilitate 75

replacement of the type bar unit at will by another type bar unit having a different style of types, said last mentioned means operating to locate the type bar unit on the bracket in operative assembly relatively to the actuator.

3. In a typewriting machine, the combination of a platen, an actuator, a shuttle element, means to support said shuttle element for oscillatory movements, a type bar support element, type bars, means to pivotally carry the type bars on said support element, and means for locating the type bar support element on the shuttle element, said means including studs on one of said elements to engage in apertures in the other element, said last mentioned means operating to demountably secure the type bar support element on said shuttle element.

4. In a typewriting machine, the combination of a platen, an actuator at the front of the platen, a unit including types disposed between said platen and said actuator, said actuator to cooperate with the types of said unit to cause them to print one at a time against the platen, a shuttle for the type unit whereby any one of the types may be positioned in registration with the actuator, a pivot for said shuttle, and means for demountably attaching said type unit on the shuttle without disturbing the shuttle pivot, said means being arranged to permit the type unit to be moved between the platen and the actuator to or from the shuttle.

5. In a typewriting machine, the combination of a type shuttle, key levers, a driving means including a constantly rotating device, intermediate mechanism whereby the shuttle may be operated by said device, said intermediate mechanism being normally disconnected from the driving means, means operable by the key levers to effect a connection of the intermediate mechanism with the driving means, said intermediate mechanism including a pawl, means operable by the key levers to effect an actuation of the pawl to connect it with the rotating device, and a locking device along which the pawl is adapted to move while being actuated by the rotating device, said locking device being effective to prevent accidental release of the pawl from the rotating device until the pawl reaches the end of said device.

6. In a typewriting machine, the combination of a type carrier having type members, a printing element to cooperate with said type members, means to support said carrier for oscillatory movement towards the opposite sides of the machine from a central position to locate any one of the type members in alignment with the printing element, key levers arranged in two groups one group at each side of the middle of the machine, settable selecting devices to determine the extent of movement of the type carrier to its printing position, means including an operating lever to actuate the shuttle in opposite directions from its normal position, an actuator to operate said lever in opposite directions from its normal position, two power driven devices, two connecting elements whereby the actuator may be connected with any one of the power driven devices according to the direction the type carrier is to be operated by said actuator, and two devices one associated with each group of key levers and with one of the connecting elements and whereby the connection of the actuating lever with one of the power devices may be effected by any key lever of the associated group through the medium of the associated connecting element.

7. In a typewriting machine, the combination

of a type carrier having type members, a printing element to cooperate with said type members, means to support said carrier for oscillatory movement towards the opposite sides of the machine from a central position to locate any one of the type members in alignment with the printing element, an operating lever for said type carrier, said lever being also operable in opposite directions from a normal position, an actuating element connected to said lever to operate it in either direction, continually running power driven devices whereby the type carrier may be operated in opposite directions from its normal position, two groups of key levers, one group associated with each power driven device, and two devices one for each group of key levers and each being operable by any one of the key levers of the associated group to effect a connection of the associated power driven device with said actuating element.

8. In a typewriting machine, the combination of a carrier having type members thereon, an element to cooperate with said type members one at a time, said element being normally at rest, selecting devices, a stop connected to said carrier, key levers one for each selecting device by which the latter is settable into the path of said stop, intermediate driving means for said carrier, continually running power means to actuate said intermediate driving means, means operable by the key levers to establish a connection of the intermediate driving means with the continually running power means, operating means for the cooperating element to cause the selected type member to print, means operable by the intermediate driving means to effect the actuation of the cooperating element, and a lock on said stop to engage the set selecting device to prevent accidental return movement of the type carrier while the cooperating element is functioning.

9. In a typewriting machine, the combination of a platen, key levers, an oscillatory support, type bars carried by said support, type bars selecting means, an actuator, power means to drive said support to position the selected type bar in alignment with said actuator, means operable by the key levers to render said power means effective, said actuator being effective to cause the selected type bar to print against said platen, and locking means independent of said actuator and on said support to prevent return movement of the latter while the selected type bar is being operated by the actuator.

10. In a typewriting machine, the combination of a carrier having type members thereon, a platen against which the type members may print an element to cooperate with said type members one at a time to cause them to print, selecting devices, a stop connected to said carrier, key levers one for each selecting device by which the latter is settable into the path of said stop, driving means for said carrier, power means to actuate said driving means, means operable by the key levers to establish a connection of the driving means with the power means, operating means for the cooperating element to cause the selected type member to print, and means operable by the driving means to effect the actuation of the cooperative element.

11. In a typewriting machine, the combination of a shuttle, type bars on said shuttle, a type bar actuator, means to position said shuttle in its printing position, the positioning means including means to drive said shuttle, continually rotating power means to actuate the driving means.

- 5 a group of key levers, said driving means being normally disconnected from the rotating power means, means operable by any one of the group of key levers to effect a connection of the driving means with the continually rotating power means, means to operate said actuator, and means engageable by the driving means to effect the actuation of the operating means to operate the type bar actuator.
- 10 12. In a typewriting machine, the combination of a shuttle, type bars on said shuttle, a type bar actuator, means to position said shuttle in its printing position, the positioning means including means to drive said shuttle, power means to actuate the driving means, key levers, means operable by the key levers to effect a connection of the driving means with the power means, means including an electric device to operate the type bar actuator, and a normally open switch 15 in circuit with said electric device, said switch being engageable by said driving means to close it to energize the electric device to actuate the type bar actuator.
- 15 13. In a typewriting machine, the combination of a shuttle having type members thereon, means including an element to cooperate with the type members individually, key levers, a fulcrum for said key levers at their rear ends, means to actuate said shuttle to locate any one of the type 20 members at the cooperating element, an upright plate above the key levers, selecting devices supported entirely on said plate one for each key lever and extended perpendicularly to said plate, upright devices one for each key lever, the upper right devices being located between the fulcrum and the keys of said key levers and extending from the key levers to the selecting devices so that the associated selecting device may be set upon an actuation of the corresponding key lever, 25 and a downwardly extending arm connected to said shuttle to swing in a plane parallel to said plate so that it may engage the set selecting device to arrest the shuttle with the type member corresponding to the actuated key lever at the cooperative element.
- 30 14. In a typewriting machine, the combination of a shuttle having type members thereon, means including an element to cooperate with the type members individually, key levers, a fulcrum for said key levers at their rear ends, means to actuate said shuttle to locate any one of the type members at the cooperating element, an upright plate above the key levers, horizontally movable selecting devices on said plate one for each key lever, said selecting devices being short and supported entirely on said plate, cams one on each key lever, said cams being located between the fulcrum and the keys of said key levers and effective to actuate the corresponding selecting device 35 by the actuation of the key lever, and a stop arm connected to said shuttle and arranged to swing in a vertical plane to engage the set selecting device to arrest the shuttle.
- 40 15. In a typewriting machine, the combination of a shuttle having type members thereon, means including an element to cooperate with the type members individually, key levers of the second order, means to actuate said shuttle to locate any one of the type members at the cooperating element, an upright plate above the key levers, short selecting devices supported entirely on said plate one for each key lever and arranged for horizontal movement on said plate, upright levers located above midway of the length of said key levers and 45 operable thereby the upper end of each upright lever engaging one of the selecting pins to actuate it upon the actuation of the corresponding key lever, and a stop arm connected to said shuttle and arranged to swing in a vertical plane to engage the set selecting device to arrest the shuttle with the selected type member at the cooperating element.
- 50 16. In a typewriting machine, the combination of a platen, a vertically disposed carrier, type bars extending outwardly from said carrier, means including an actuator arranged in front of the platen by which any one of the type bars may be actuated to print against said platen, a vertically disposed plate, fixedly supported means by which said carrier is pivotally supported for oscillatory movements toward either side of the machine from a normal or central position, means for actuating said carrier, a series of selecting devices one for each type bar, said selecting devices being supported on said plate and arranged in an arc about the pivot of said carrier, horizontal key levers under said plate, cam members extending upwardly from all of said key levers, the cam members of the key levers near the middle of the machine engaging directly with the corresponding selecting devices to set them, intermediate levers extending upwardly from the cam members of the key levers near the sides of the machine to the outer ones of the series of selecting devices and whereby the outer selecting devices 55 may be set, and a downwardly extending arm on said carrier to engage any one of said selecting devices which may be in its set position to arrest the carrier with the selected type bar at the type bar actuator.
- 60 17. In a typewriting machine, the combination of printing instrumentalities including a type shuttle, actuating means for said shuttle, and selectively settable stops to arrest the shuttle in various angular positions, the actuating means including a continually rotating power device, an actuator for the shuttle, an element normally ineffective but connectable to and operable by said power device to drive the actuator by the power device, means to render the connecting element 65 effective, means to retain said element connected so that the actuator is always driven through a constant distance, and a compensating power transmitting device between the connectable element and said actuator.
- 65 18. In a typewriting machine, the combination of printing instrumentalities including a type shuttle, operable in opposite directions from a normal position, actuating means for said shuttle, and selectively settable stops to arrest the shuttle in various angular positions, the actuating means including a continually running power device, an actuator for the shuttle operable in opposite directions to accordingly drive the shuttle in opposite directions, two elements normally ineffective but connectable individually to said power device and actuatable thereby always through a constant distance to operate the actuator in opposite directions by said power means, and two compensating power transmitting devices one between 70 each connectable element and said actuator.
- 70 19. In a typewriting machine, the combination of a series of type bars, a swingable shuttle, a holder for said type bars, means including a finger-piece in an accessible position to demountably secure said holder on said shuttle and to facilitate replacement of said holder by another one having a different style of types on its type bars, means for swingingly supporting said type bars on said holder, a type bar actuator, means for 75

operating said shuttle to locate any one of the type bars at said actuator, and key levers each being separably cooperable with said operating means, the actuator and the shuttle being located with respect to each other so that the type bar holder may be detached without disturbing said actuator or said shuttle.

20. In a typewriting machine, the combination of a swingable type bar carrier, a platen, a hammer cooperable with any one of the type bars of said carrier to cause it to print against said platen, a continually rotating power driven shaft, means operable by said continually rotating power shaft to actuate said carrier, and means independent of said continually rotating power shaft for positioning the type bar carrier so that the desired type bar is in striking alignment with said hammer, said hammer and said type bar carrier being located at the front of the platen so that a work sheet may be inserted around the platen from the rear thereof.

21. In a typewriting machine, the combination of a platen, a swingable type carrier, type bars on said carrier, a hammer cooperable with the type bars to actuate any one of them to print against said platen, a continually rotating power driven shaft, means operable by said continually rotating power shaft to actuate said carrier, a series of key levers, and devices operable by the key levers to determine the extent of movement of said carrier for the purpose of positioning any one of the type bars of said carrier in striking alignment with said hammer.

22. In a typewriting machine, the combination of a platen, a swingable type carrier, type bars on said carrier, a hammer cooperable with the type bars to actuate any one of them to print against said platen, a power shaft, means cooperable with said carrier and said power shaft for actuating the type carrier in opposite directions from a normal position to locate any one of the type bars of said carrier in striking alignment with said hammer, a series of key levers, and a series of stop pins, one for each key lever, each pin being operable by its key lever into the path of travel of said carrier to arrest the carrier in a position with the desired type bar in alignment with said hammer, the type bar carrier and said hammer being located at the front of the platen so that a work sheet may be passed around said platen to the printing point from the rear thereof.

23. In a typewriting machine, the combination of a shuttle, a demountable holder on said shuttle, type bars on said holder, means whereby the holder may be readily and detachably secured to the shuttle for the purpose of substitution by another holder having types of a different style, an actuator common to all of the type bars, and means to actuate the shuttle while the holder is secured to said shuttle to carry any one of the type bars of said holder into cooperative relation with said actuator.

24. In a typewriting machine the combination of a shuttle, a demountable holder on said shuttle, type bars on said holder, means whereby the holder may be readily and detachably secured to the shuttle for the purpose of substitution by another holder having type bars with another style of types, an actuator common to all of the type bars, means to actuate the shuttle while the holder element is secured to said shuttle to carry any one of the type bars of said holder into cooperative relation with said actuator, and means to accurately position said shuttle in its various printing positions, the positioning means being

free and clear of the type bar holder so as not to interfere while changing the type bar holder.

25. In a typewriting machine, the combination of a shuttle, a demountable holder on said shuttle, type bars on said holder, means whereby the holder may be readily and detachably secured to the shuttle for the purpose of substitution by another holder having type bars with another style of types, an actuator common to all of the type bars, means to actuate the shuttle to carry any one of the type bars of said holder into cooperative relation with said actuator while the holder element is secured to said shuttle, and means to lock the shuttle in its various printing positions, the locking means being associated with the shuttle and being free and clear of the type bar holder so as not to interfere while changing the type bar holder.

26. In a typewriting machine, the combination of a shuttle, a demountable holder on said shuttle, type bars on said holder means to actuate said shuttle to drive it to any one of its printing positions, means cooperating with said shuttle to accurately position the desired type bar at the printing point, and means to demountably support and accurately position the type bar holder on the shuttle with respect to the positioning means and for the purpose of readily substituting the type holder by another one having a different style of types.

27. In a typewriting machine, the combination of a shuttle, a demountable holder on said shuttle, type bars on said shuttle, means to actuate said shuttle to drive it to any one of its printing positions, means cooperating with said shuttle to accurately position the desired type bar at the printing point, means including a member on the shuttle to assist in locking the shuttle in any one of its printing positions with the desired type bar at the printing point, and means to demountably support and to accurately locate the type bar holder on the shuttle with respect to the said member so that it may readily be substituted by another type bar holder having a different style of types.

28. In a typewriting machine, the combination of a type carrying shuttle, means to support said shuttle for oscillatory movements with respect to a printing point, shuttle actuating means including a gear secured to said shuttle and a rack operable in opposite directions to drive said gear, a demountable type carrier on said shuttle, and means to accurately locate said carrier concentrically and angularly with respect to said gear.

29. In a typewriting machine, the combination of a platen, an oscillatory type carrier, type bars on said type carrier, a power device to actuate said type bar carrier selectively in opposite directions from a normal position, key levers, pins selectable by the key levers to determine the extent of angular movement of the type carrier, the key levers being divided into two groups, and two devices one for each set of key levers and each being operable by any one of the key levers of the associated group to determine the direction of actuation of the type bar carrier by the power device, and to render the power device effective.

30. In a typewriting machine, the combination of printing instrumentalities including an oscillatory type carrier which may be moved in opposite directions from a normal position to selectively position any one of the types thereon at the printing point, means including an operating lever connected to said type carrier, said lever being operable in opposite directions from a nor-

mal position to correspondingly actuate the type carrier, means including two clutches normally ineffective but whereby the continually rotating power element may be connected differently with the type carrier to drive the latter in either direction, two groups of key levers arranged side-by-side each group having one of the clutches associated therewith, two universal bars one for each group of key levers and each universal bar being operable by any one of its associated key levers, means operable by each universal bar to render the associated clutch element effective so that the operating lever may be actuated by the power element, and devices selectable by the key levers to determine the extent of operation of the type carrier by the power element.

31. In a typewriting machine, the combination of a platen, a movable support, type bars on said support, said type bar support being supported in an upright position in front of said platen and to move in a plane transversely of the machine, a hammer to engage any one of the type bars to cause it to print against the platen, a power shaft, means operable by the power shaft to actuate the type bar support to thus position a desired type bar in alignment with the hammer, key levers, and pins to determine the extent of movement required of said type bar support to locate the desired type bar at said hammer, and means actuable by anyone of said key levers to cause the operable means to be actuated by the power shaft, any one of said pins being rendered effective by a corresponding key lever prior to the actuation of the type bar support.

32. In a typewriting machine, the combination of printing instrumentalities including a type carrier, a horizontal pivot extending fore-and-aft of the machine about which the type shuttle may be actuated towards either side of the machine from a normal position, key levers, a vertical plate extending transversely of the machine and arranged above the key levers, settable stop pins on said plate, said pins being arranged in an arc extending around the axis of said pivot, an arm on said type carrier to engage any one of said pins to arrest the type carrier in its various positions, upwardly extending members on the key levers near the middle of the machine to engage the stop pins near the middle of said plate, two groups of intermediate levers each group being associated with the key levers near the side of the machine, and two fulcrum rods, one at each side of said plate whereby the two groups of intermediate levers are pivotally supported on said plate, the lower ends of the intermediate levers being engageable by the associated key levers to actuate the intermediate levers, the intermediate levers slanting upwardly and inwardly of the machine so that their upper ends engage the pins at the outer ends of the set to actuate them, the fulcrum rods slanting upwardly and outwardly on said plate.

33. In a typewriting machine, the combination of printing instrumentalities including a type carrier rotatable about a fixed axis, means including a power shaft, intermediate means between said power shaft and said type carrier whereby the type carrier may be actuated by the power shaft, a group of key levers, a connecting element common to the key levers of the group whereby the intermediate means may be connected with the power shaft, key levers, means including a device operable by any one of the key levers to render said connecting element effective, and means independent of the rendering means to retain the

connecting element in its connected position until after the type carrier has been moved to position the selected type at the printing point.

34. In a typewriting machine, the combination of printing instrumentalities including a type carrier rotatable about a fixed axis, means including a power shaft, intermediate means between said power shaft and said type carrier whereby the type carrier may be actuated by the power shaft, key levers, a connecting element whereby the intermediate means may be connected with the power shaft, means operable by the key levers to render said connecting element effective, and a plate along which the connecting element travels, said plate being effective to lock the connecting element in its connected position until after the type carrier has been located in its selected position.

35. In a typewriting machine, the combination of a platen, a movable type carrier having a horizontal axis, stop pins adapted to be located in the path of travel of said carrier, type bars on said carrier, a hammer cooperable with the type bars to actuate them one at a time against said platen, a power shaft, means cooperable with said carrier to actuate the type bar carrier in opposite directions from a normal position for positioning any one of the type bars in striking alignment with said hammer, key levers, and other means adapted to be actuated by any of said key levers for engaging said first mentioned means with said power shaft.

36. A writing machine having a platen, a swingable type carrier disposed in an upright position forwardly of said platen and in a plane extending parallel to the axis of the platen, type bars on said carrier a hammer cooperable with the type bars of said carrier, a power shaft, means cooperable with said carrier and said power shaft to actuate said carrier for positioning the type bars of said carrier in striking alignment with said hammer, a projection on said carrier, and a series of stop pins each being operable into the path of travel of said projection to arrest said carrier.

37. A writing machine having a platen, a swingable type carrier disposed in an upright position forwardly of said platen and in a plane extending parallel to the axis of the platen, type bars on said carrier, a hammer cooperable with the type bars of said carrier, a power shaft, means cooperable with said carrier and said power shaft to actuate said carrier for positioning the type bars of said carrier in striking alignment with said hammer, a series of stop pins each being operable into the path of travel of said carrier, and a series of key levers each having cooperation with said means and a respective stop pin.

38. A writing machine having a platen, an oscillatory type carrier disposed forwardly of said platen, a hammer cooperable with the type of said carrier to print against said platen, a power shaft, intermediate means cooperable with said carrier, said intermediate means including a member to be engaged with said power shaft to connect it therewith so that the intermediate means may be actuated by the power shaft for positioning the type carrier in striking alignment with said hammer, stop pins adapted to be positioned in the path of travel of said carrier, key levers each being cooperable with a respective stop pin, other means adapted to be actuated by any of said key levers for engaging said member of the intermediate means with said power shaft, and means to return said intermediate means and the type carrier independently of the power shaft.

39. In a typewriting machine, the combination of a platen, a type bar carrier, type bars thereon, means by which the type bars are pivotally mounted on the carrier, a type bar actuator, means to actuate the type carrier to selectively position any one of the type bars at the type bar actuator, each type bar being detachable for replacement, and means to demountably support the type carrier on the actuating means therefor so that the type carrier may readily be substituted by another one for printing with another style of types.
40. In a typewriting machine, the combination of a platen, means including a rotatable device having two opposite faces, a stationary bracket adjacent to one face of said device, means to rotatably support said device on said bracket, a carrier element having type bars thereon to print against said platen, and means for detachably mounting said carrier element on said device at the face opposite to the first mentioned face of said device so as to give ready access to the mounting means for the purpose of conveniently attaching or detaching the type bar carrier element.
41. In a typewriting machine, the combination of a platen, a rotatable device, stationary means about which said device may be rotated, a carrier element having type bars thereon to print against the platen, said carrier element extending about
- the axis of said device, means to detachably support said carrier element on said device, means to actuate said device to register any one of the type bars at the printing point, and means to secure the type bar carrier element to prevent accidental displacement on said device while the latter is being actuated.
42. In a typewriting machine, the combination with a platen, and printing instrumentalities including type bars to print against said platen, of two separable elements, means to rotatably support one of said elements, the type bars being supported on the other one of said elements, and means including members on one of said elements to cooperate with portions on the other element to locate the type bar carrying element accurately on the rotatable element, said last mentioned means operating to secure the type bar carrying element on the rotatable element.
43. In a typewriting machine, the combination of a support, type elements detachably mounted on said support so that any one of them may be substituted by another one, means to actuate said support to selectively register any one of the type elements with the printing point, the actuating means including a bracket, and means for demountably attaching said support to said bracket so that it may readily be substituted by another support having a different kind of types.

W. J. HAUSMAN. 30
